UNITED STATES PATENT OFFICE.

THOMAS J. BONNIWELL, OF CHICAGO, ILLINOIS.

STRIPPING MECHANISM FOR WRINGER-ROLLS.

1,375,356.

Specification of Letters Patent. Patented Apr. 19, 1921.

Application filed October 2, 1919. Serial No. 327,977.

To all whom it may concern:

Be it known that I, THOMAS J. BONNIWELL, a citizen of the United States, and a resident of the city of Chicago, in the county 5 of Cook and State of Illinois, have invented certain new and useful Improvements in Stripping Mechanism for Wringer-Rolls, and I do hereby declare that the following is a full, clear, and exact description of the 10 same, reference being had to the accompanying drawings, and to the numerals of reference marked thereon, which form a part of this specification.

This invention relates to an attachment 15 for a wringer to provide a means for preventing articles after passing between the wringer rolls from becoming wrapped around either thereof by stripping or diverting the articles from the rolls if any 20 tendency for the articles to cling to the rolls occurs.

It is an object therefore of this invention, to construct a wringer having a plurality of adjustably mounted stripper bars 25 adjustable to any position according to wearing of the rolls, for contact with the wringer rolls on each side of each roll to effectually prevent adhering of articles to the rolls for either direction of operation 30 thereof.

Other and further important objects of this invention will be apparent from the disclosures in the drawings and specification.

35 The invention (in a preferred form) is illustrated in the drawings and hereinafter more fully described.

Drawings.

40 Figure 1 is a front elevation partly broken away showing a wringer equipped with devices embodying the features of my invention.

Fig. 2 is a fragmentary transverse ver- 45 tical section therethrough.

Fig. 3 is a detail section on line 3—3 of Fig. 2.

Fig. 4 is a detail section on line 4—4 of Fig. 2.

50 Description.

The wringer consists of end uprights 1 and 2, between which are journaled wringer

rolls 3 and 4 in a usual and well known manner. The shafts for the wringer rolls 55 are provided with intermeshing pinions 5 and 6, to insure positive and simultaneous operation of both rolls in opposite directions when one thereof is operated in the usual manner, by means of a crank placed 60 upon the shaft extension 7. A water drain board 8, is mounted beneath the lower roll in a usual manner.

Secured between the uprights 1 and 2, on each side of the wringer, are transverse 65 boards 9, positioned slightly above the upper roll 3, and transverse bars 10 are also secured on each side of the wringer to the uprights 1 and 2, slightly below the roll 4.

The stripper bars for the upper roll are 70 shown clearly in Fig. 2, and are designated by the reference numerals 11. They are preferably, though not necessarily, constructed of wood, but of course may be of metal or other material, having beveled 75 lower surfaces which rest by gravity upon the top surface of the roll 3. At each end of each of the stripper bars 11, transverse pins or rods 12 are provided, extending therethrough so that the bars are loosely retained thereon, permitting adjustment of the stripper bars also to fit any size roll. Said rods 12, have no connection with the wringer frame, but merely abut against the bars 9, and prevent overturning of the stripper bars 85 11, resting by gravity on the roll 3 when the roll 3 revolves. As shown, the uprights 1 and 2 are provided on their inner surfaces with angle irons 13, which constitute a part of the usual wringer constructions. The 90 stripper bars 11, are provided with block sections or extensions 14 at their ends, which are squared off to rest in the upright angle bars 13, and serve also to prevent overturning of the stripper bars 11 on the wringer 95 roll.

Beneath the lower wringer roll 4, another set of stripper bars 15 is provided, which at their ends are loosely engaged on transverse rods 16, loosely mounted in the 100 wringer frame, and abutting the boards 10. For the purpose of retaining the lower stripper bars 15 upwardly in contact with the undersurface of the roll 4, a pair of springs 17 are provided for each of the stripper 105 bars, bearing upwardly therebeneath near

each end thereof and secured in position on the respective boards 10.

Operation.

5 The upper stripper bars 11, rest upon the top roll 3 by gravity, the beveled lower surfaces thereof riding upon the surface of the roll. The rods 12 which extend loosely through each end of the stripper bars 11, 10 prevent overturning thereof, and said rods at their ends abut against the boards 9.

In some types of wringer constructions, the boards 9 are omitted, but generally the upright angle irons 13 form a part of this 15 structure, and these may be utilized to prevent overturning of the stripper bars 11. Accordingly, I have shown block sections 14, secured to or forming a part of the stripper bars 11, engaging loosely in the upright 20 angle bars 13 and serving to prevent overturning of the stripper bars. Either the rods 12 may be used, or the angle bars 13 and block sections 14, to prevent overturning 25 of the stripper bars, but this will depend upon the type of wringer with which the stripper bars are associated.

Similarly the lower stripper bars 15 contact against the under surface of the roll 4, and are held thrust upwardly against the 30 roll by the leaf or any other type of springs 17, secured to the boards 10. Similarly the transverse bars 16, loosely engaged through the stripper bars 15, prevent overturning of the stripper bars by rotation of the roll.

35 It is obvious that many other ways and means for disposing, attaching or assembling the stripper bars with the wringer are possible whereby the stripper bars are held in operative relation by gravity or resilient 40 means, and capable of displacement movement from the rolls, but all such modifications fall well within the scope of my invention. In place of two stripper bars

shown for each roll, it is possible to use only one, and if desired it may be curved 45 substantially to the contour of the roll at its contacting portion therewith.

I am aware that many changes may be made, and numerous details of construction may be varied through a wide range without 50 departing from the principles of this invention, and I therefore do not purpose limiting the patent granted otherwise than necessitated by the prior art.

55

Claims.

1. In a wringer, the combination with the rolls thereof, of stripper bars contacting with the rolls, and means for securing said bars in place, comprising a transverse rod 60 at each end, extending transversely through said bars, to non pivotally secure said bars within the wringer frame.

2. In a wringer, the combination with the rolls thereof, of a pair of parallel stripper 65 bars arranged to contact with each roll, a plurality of transverse rods extending through each pair of bars to non pivotally support the same inclosed within the wringer frame.

70 3. In a wringer the combination with the rolls thereof of a pair of beveled stripper bars contacting with the sides of a roll and a plurality of rods extending transversely of said bars for supporting said bars for adjustable sliding movement to accommodate the same for different sized rolls and to take up wear.

In testimony whereof I have hereunto 75 subscribed my name in the presence of two 80 subscribing witnesses.

THOMAS J. BONNIWELL.
